FLUID HEAT EXCHANGE APPARATUS

Charles U. Savoye, Hackensack, N. J., assignor to
The Babcock & Wilcox Company, Newark, N. J.,
a corporation of New Jersey

Application September 14, 1938, Serial No. 229,801

5 Claims. (Cl. 122—235)

This invention relates to fluid heat exchange apparatus operating at high temperatures. It is more particularly concerned with apparatus of this type in which heat is transmitted from a furnace which is fired by burning of fuel at temperatures above the fusion point of the ash of the fuel.

The invention may be considered as exemplified by a water tube steam boiler. Such a boiler has one or more banks of closely spaced tubes exposed externally to the furnace gases so that the fluid within the tubes is heated. When the boiler furnace is provided with water walls the steam may be generated in the tubes of those walls, and when the steam pressure is high and the steam is superheated to a high temperature so that the ratio of superheat to the latent heat of vaporization is high, there may be no deep bank of steam generating tubes extending across the path of the furnace gases.

The gases passing from the furnace and approaching the first closely spaced tube bank, whether it be formed of steam generating tubes or steam superheating tubes, must be limited as to temperature when the fuel contains ash. This limitation is necessary in order to prevent the ash particles in the gases from being soft enough to stick to the closely spaced tubes and obstruct the gas flow spaces between them.

When the furnace temperature is higher than the allowable entrance temperature to the tube bank, as is good practice in the interests of effective combustion, the furnace exit gases must be cooled before they reach the tube bank, and the means for cooling the gases must be such that there will be no excessive obstruction to gas flow by the collecting of slag or ash.

When the furnace gases approach a superheater tube bank they must be limited in their temperature to such a value that the superheater tube metal will not be overheated, and the gases must be cooled to such a temperature range when previously they have had a higher temperature. In some cases, there is a bank of steam generating tubes in front of the superheater for this purpose, but in other cases they are not needed because of the steam generating capacity of the furnace water walls, and then the cooling of the hot exit gases to the allowable superheater gas temperature must be otherwise accomplished.

The invention relates to means for accomplishing the above indicated results, said means being of wide application to a variety of boilers including those with straight tubes between headers.

Other objects of the invention will appear as the following description proceeds.

The invention will be described with reference to the preferred embodiments thereof which are shown in the accompanying drawings.

In the drawings:

Fig. 1 is a view in the nature of a vertical section through a steam boiler embodying the invention;

10 Fig. 2 is a transverse section on the line 2—2 of Fig. 1, and looking in the direction of the arrows;

Fig. 3 is a transverse vertical section on the section line 3—3 of Fig. 1, looking in the opposite direction, as indicated by the arrows;

15 Fig. 4 is a diagrammatic view illustrating another embodiment of the invention in transverse vertical section;

Fig. 5 is a transverse vertical section on the line 5—5 of Fig. 6; and

20 Fig. 6 is a vertical section through a steam boiler employing the invention.

In carrying out the invention there are provided sets of water tubes such as those indicated by the reference characters 10—15, inclusive, in Fig. 5 of the drawings. These tubes extend across the furnace gas stream and they are connected into the boiler circulation to and from the drum 18 so as to be supplied with water for the generation of steam.

25 The sets of tubes 10—15, inclusive, are arranged so as to cool the furnace gases and they are arranged in rows, with wide spaces between the rows. The tubes of each set extend upwardly from the cross header 20 (Fig. 1 and Fig. 6) and are bent so that their major portions provide a widely spaced arrangement of longitudinal rows. The outlet ends of these tubes extend upwardly and are connected to the uptake headers 22 as indicated in the drawings.

30 The wide spacing of the sets or rows of tubes 10—15, inclusive, provides gas bodies radiating to all of the tubes within sight of them, and the greater the mean thickness of each gas body, or equivalent mean length of radiating rays, the greater will be the hourly gas radiation rate per square foot of tube surface. The illustrative arrangement provides separate gas bodies of considerable mean thickness, so that the length of 35 path of gases radiating to the widely spaced tubes and the surfaces of such tubes receiving such radiation are such that the furnace gases are cooled to the temperatures required at the tube bank 24 beyond the gas cooling, or slag screen tubes.

40 The wide spacing of the tubes of the sets 10—15,

inclusive, is responsible for a small draft loss as the gases cool by their own radiation and by convection, and this is a matter of considerable importance. It is especially important when sticky ash or slag is present. This ash or slag adheres to the tubes below the bank 24 but it cannot materially increase the draft loss or hourly gas flow capacity for a given draft. As the slag accumulates on one of these tubes, the outer face of it is in contact with the furnace gases. It rises in temperature because of the increased thermal resistance and constant tube temperature. This action continues until the outer face of the slag accumulation reaches the temperature at which the slag is fluid and runs off by gravity. This fixes a maximum thickness of slag on the sides of the tubes below the bank 24, and by making the horizontal spaces between these tubes a large multiple of this thickness, a most substantial reduction of gas flow area is possible.

In the installation indicated in Fig. 6 of the drawings the furnace 30 is provided with water cooled walls such as those indicated at 32 and 34, and it is fired by pulverized fuel burners 36 and 38. In the zone of the furnace adjacent the burners 36 and 38 the walls of the furnace may be lined with ceramic refractory material held in place by the wall cooling tubes such as those indicated at 40 and 42. This burner zone 44 may have the wall tubes within that zone provided with metallic studs or other extensions welded to the tubes and distributed over the inner faces thereof in such a manner as to maintain the ceramic refractory material in position.

In the furnace zone above the burners 36 and 38 the furnace walls may be lined with wall blocks secured to the wall cooling tubes, and the hopper 46 below the zone 44 may have its sides formed by metallic blocks secured to the wall cooling tubes and closing the spaces between them.

The furnace gases pass upwardly through the furnace and into the cavity radiation chambers between the sets of tubes 10-15 inclusive. These tubes are indicated as horizontally inclined tubes extending across the upper portion of the furnace from the header 20 and entering the sectional headers 48 at their lower ends. The sectional headers 48 communicate with the outlet ends of the steam generating tubes of the bank 24, and these tubes are supplied with water at their lower ends by downtake headers 50 having their upper ends in direct communication with the water space of the drum 18 by the conduits 52. The cross header 20 is supplied with water by reason of its direct connection with the lower ends of the downtake headers 50, afforded by the tubes 54.

The upper ends of the sectional headers 48 are connected with the steam space of the drum 18 by the risers 56, the upper parts of which form the horizontal circulators 58.

In the particular installation indicated in Fig. 6 of the drawings the furnace gases pass upwardly beyond the bank of steam generating tubes 24 in two parallel passes 60 and 62. These passes are separated by a baffle 64 defined by the upper row of tubes 66 of the bank 24. These tubes extend from the tops of the sectional headers 50 to an intermediate header 70 which is connected to the steam space of the drum 18 by other tubes defining the upper part of the baffle 64.

A superheater 74 is arranged in the gas pass 75

60 and an economizer section 76 is positioned within the gas pass 62. Another economizer section 78 is disposed in the upper parts of the gas passes 60 and 62, and above this section dampers 5 80, 81, and 82 are arranged so as to control the proportioning of the flow of furnace gases between the two parallel passes 60 and 62.

With reference to Fig. 2 of the drawings, it will be noted that the set 10 of slag screen tubes 10 have their inlet ends bent laterally at different distances above the cross header 20. For instance, the second tube 90 from the left, has its portion 92 bent to the left so that the steam generating portion 94 of that tube is in line with the steam generating portion 96 of the first tube, and similarly the inlet portions of tubes 98 and 100 are bent so as to bring their steam generating portions 102 and 104 into alignment with the steam generating portions of the lower tubes. A succeeding group of the screen tubes 108-108, inclusive, are similarly bent so that they may form the set of tubes 14. This arrangement is continued across the entire furnace.

Fig. 3 of the drawings shows the manner in which the screen tubes comprising the sets 10-15 inclusive are bent at their outlet ends. In a sense, the bends of these tubes are reversely arranged with respect to the bends of the inlet ends of the same tubes.

Fig. 1 indicates the gas tight seal 110 between the header 20 and the water wall defined by the tubes 42. It also shows a similar seal 112 at the opposite side of the furnace so as to prevent gas leakage between the water wall defined by the tubes 40 and the uptake headers 48 above that wall. Both seal constructions permit relative movement between the water walls and the headers 20 and 48.

Fig. 4 of the drawings shows another arrangement of the screen tubes below the bank of tubes 24. In this instance, the screen tubes are arranged in rows 120-126, inclusive, disposed obliquely with reference to the direction of flow of the furnace gases.

While the invention has been described with reference to the particular embodiments shown in the drawings, it is to be appreciated that it is not limited to all of the details thereof. These may be modified in different combinations, within the scope of the subjoined claims.

I claim:

1. In a water tube steam boiler, a furnace fired with a slag forming fuel, a bank of spaced fluid heating tubes extending across the flow of hot gases from the furnace, an uptake communicating with the discharge ends of the tubes, a downtake communicating with the inlet ends of the tubes, a cross header below said tubes, means connecting the downtake with the header, and slag screen tubes connected to the header in a row longitudinally of the header, said screen tubes having steam generating portions extending in parallelism across the flow of gases at a position forwardly of said bank of tubes and arranged in rows in planes transversely related to the horizontal axis of the header, the ends of the slag screen tubes remote from the header being bent upwardly toward the uptake.

2. In a water tube steam boiler, a furnace, means associated with the furnace for burning a slag forming fuel at temperatures above the fusion point of the ash, and a bank of convection-heated tubes extending across the path of the combustion products passing from the furnace,

the combination therewith of sectional uptake and downtake headers at opposite ends of the tubes of said bank, a cross header disposed at the downtake header side and at a level considerably below the lower ends of the downtake headers, tubular means connecting the lower ends of the downtake headers with said cross header, and slag screen tubes having their inlet ends connected to the cross header and their intermediate portions widely spaced and arranged in parallelism across the gas pass at a position between the first mentioned tubes and the furnace, said slag screen tubes having upwardly extending discharge ends communicating directly with the lower ends of the sectional uptake headers.

3. In a water tube steam boiler, a furnace, means associated with the furnace for burning a slag forming fuel at temperatures above the fusion point of the ash, and a bank of horizontally inclined tubes extending across the path of the combustion products passing from the furnace, the combination therewith of uptake and downtake header constructions at opposite ends of the tubes of said bank, a cross header disposed at the downtake header side and at a level considerably below the downtake header structure, tubular means connecting the downtake header construction with said cross header, and slag screen tubes having their inlet ends connected to the cross header and their inclined intermediate portions widely spaced and arranged in parallelism across the gas pass at a position between the first mentioned tubes and the furnace, said slag screen tubes having upwardly extending discharge ends communicating directly with the uptake header construction.

4. In a water tube steam boiler, a furnace, means for burning fuel in the furnace, and a bank of convection heated tubes extending across the path of the products of combustion passing from the furnace, the combination therewith of uptake and downtake means at opposite ends of the tubes of said bank, a cross header in the nature of a tubular unit extending transversely of said bank of tubes and disposed at the downtake side and at a position below the downtake means, tubular means for connecting said cross header into the fluid system of the boiler, and other tubes having their inlet ends connected to the cross header and their intermediate portions arranged in parallelism across the gas pass at a position between the first mentioned tubes and the furnace, said other tubes having upright discharge ends leading directly upwardly to the lower end of the uptake means.
5. In a steam boiler, a furnace, fuel burner means associated with the furnace, means forming a gas pass leading from the furnace, a plurality of spaced and parallel groups of convection heated tube sections extending across the gas pass to form a bank, the tube sections of each group being spaced from each other and arranged in an upright row, and means including integral extensions of said tube sections at opposite sides of the gas pass for connecting the sections into the water circulation of the boiler, the integral extensions having straight upright portions disposed in upright rows at opposite sides of the gas pass, the axes of the straight portions being transversely related to the longitudinal axes of the associated sections.

CHARLES U. SAVOYE.
